UNITED STATES PATENT OFFICE.

HUBERT L. WHITELAW, OF ST. LOUIS COUNTY, AND WALTER G. VOLLMER, OF ST. LOUIS, MISSOURI, ASSIGNORS TO JESSE M. WILLIAMS, OF SANTA MONICA, CALIFORNIA.

RADIATOR.

Application filed December 1, 1922. Serial No. 604,820.

To all whom it may concern:

Be it known that we, HUBERT L. WHITELAW, a citizen of the Dominion of Canada, a resident of the county of St. Louis, State of Missouri, and WALTER G. VOLLMER, a citizen of the United States, a resident of the city of St. Louis, State of Missouri, have invented certain new and useful Improvements in Radiators, of which the following is a full, clear, and exact description, reference being had to the accompanying drawings, forming a part of this specification.

This invention relates to improvements in radiators, one of the objects being to produce an efficient combination boiler and radiator having a combustion chamber containing a burner, said combustion chamber being provided with a movable end wall whereby the length of said combustion chamber may be regulated.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a front elevation, partly in section, illustrating a radiator embodying the features of this invention.

Fig. II is a fragmentary cross section of the lower portion of my improved radiator showing the adjustable end wall of the combustion chamber.

Fig. III is a section on line III—III of Fig. II.

The radiator shown in the drawings comprises end sections A' and B' provided with legs 1 whereby all of the intermediate sections are supported above the floor. A designates what we will term "boiler sections," arranged in a horizontal row and alined with "heat-radiating sections" B. Upper and lower tie rods 2 pass through all of the sections, said rods having nuts at their ends which may be adjusted to securely unite the sections.

All of these sections are hollow and their upper ends are connected by means of tapering nipples 3 (Fig. I) which place all of the

sections in communication with each other, excepting the end section B', which lies farthest from the boiler sections A, and which does not have its upper end in direct communication with the next adjacent section, a plug, or closure 3', being used at this point (Fig. I). To establish communication between the lower ends of all of the sections, tapering nipples 4 are used, these nipples forming part of a continuous water-passageway wherein water is returned from the sections B and B' to the boiler sections A and A'.

Each boiler section has a recess open at the bottom of the section, and the several recesses are in horizontal alinement with each other to produce an elongated combustion chamber C, said chamber having top and side walls formed partly by hollow portions of the sections and partly by mating ribs 5 extending from the sides of the section. In addition to this, each boiler section A is provided with a tubular water-receiving bridge 6 extending across the combustion chamber and communicating with the fluid passageways in the boiler sections. The several bridges 6 are connected together through the medium of the nipples 4. An angular flue 7, formed integral with one of the boiler sections, extends from the top of the combustion chamber at a point approximately midway between the ends thereof, and leads to one side of the radiator. Immediately below the entrance to the flue, one of the tubular bridges has a tapering upstanding baffle rib 8 to deflect the oppositely moving products of combustion to the flue.

The end walls of the combustion chamber are formed partly by a web 9 on the end section A' and partly by a plate 10 which can be removed and located in different positions to vary the length of the combustion chamber. The plate 10 has rounded lugs 11 at its upper edge adapted to closely fit in spaces between the tubular bridges 6 in the boiler sections, or between similar bridges 6' in the heat-radiating sections. These lugs can also fit between one of the bridges 6 and one of the bridges 6', as shown in Fig. I.

The lower portions of the hollow sections are provided with notches 12 to receive portions of the plate 10. To remove this plate, it is lifted from the notches 12 and then tilted while its upper edge is withdrawn

from the tubular bridges. To permit the lifting movement, the upper edge of plate 10 is notched at 13 (Fig. II) so as to clear the projecting rib around the nipple 4. The lugs 11 at the upper edge of said plate are adapted to fit between any of the adjoining tubular bridges 6 or 6', and the lower portions of this plate are adapted to enter any pair of the oppositely disposed notches 12.

19 The bottom of the combustion chamber C is open to receive a gas burner 14 which lies within the lower portion of the combustion chamber and extends approximately from end to end thereof. By having the combustion chamber open at the bottom, the burner can be dropped onto the floor below the radiator and it can be readily placed in the combustion chamber. The open bottom also serves as an outlet for burned matches 20 dropped in lighting the burner and falling to the floor instead of collecting in the combustion chamber and causing an odor. Furthermore, the secondary air for combustion freely enters the open bottom of the combustion chamber at all points throughout the 25 length of the burner.

Primary air enters through a return bend 15 (Fig. I) at the outer end of the burner. The gas-controlling means comprises a manually operated valve 18 on a housing 19 and a safety valve 25 (Fig. I) is applied to the end section A'.

30 The outer end of the burner 14 is supported by a screw-threaded nipple 26 and a threaded union 27 whereby gas is conducted from the housing 19 to the passageway 16. To support the burner at different elevations relative to the combustion chamber, a longer or shorter nipple can be substituted for the 35 nipple 26. For the same reason the plate 10 at the inner end of the combustion chamber has two holes 28 formed one above the other to receive an extension 29' on the inner end of the burner. The burner lies between 40 two vertical walls and it can be adjusted vertically without varying the width of the spaces through which air is admitted at opposite sides of the burner. The main object 45 of the vertical adjustment of the burner relative to the top of the combustion chamber

is to obtain the highest efficiency under different conditions.

The steam generated in the boiler sections A and A' rises freely to the top of the radiator where the nipples 3 establish communication between all of the sections, and the air is expelled through an air valve 30 (Fig. I) on the heat-radiating section B' farthest from the boiler, the upper end of this section being closed by the nipple 3' which 55 serves as a plug to prevent direct communication between this upper end and the next adjacent section.

We claim:

1. In a sectional radiator, a row of hollow 60 sections having a combustion chamber in their lower ends, said combustion chamber having an end wall adjustable longitudinally of the combustion chamber to vary the length thereof with respect to the length of 70 the radiator, and a burner in said combustion chamber.

2. In a sectional radiator, a row of hollow sections each having an opening in its lower end, the openings being alined with 75 each other to form a combustion chamber, an end wall for said combustion chamber adjustable from one of said sections to another to vary the length of the combustion chamber 80 with respect to the length of the radiator, and a gas burner in said combustion chamber.

3. In a sectional radiator, a row of hollow sections each having an opening in its lower 85 end, the openings being alined with each other to form a combustion chamber, an end wall for said combustion chamber adjustable from one of said sections to another to vary the length of the combustion chamber, said sections having separated portions forming 90 recesses wherein said end wall is removably interlocked with the sections, and a gas burner arranged in said combustion chamber and having one of its ends supported by 95 said end wall.

In testimony that we claim the foregoing we hereunto affix our signatures:

HUBERT L. WHITELAW.
WALTER G. VOLLMER.
